UNITED STATES PATENT OFFICE

EDGAR C. BRITTON AND WILLIAM ROBERT REED, OF MIDLAND, MICHIGAN, ASSIGNEES
TO THE DOW CHEMICAL COMPANY, OF MIDLAND, MICHIGAN, A CORPORATION OF
MICHIGAN

METHOD OF MAKING HALOGENATED AROMATIC HYDROCARBON DERIVATIVES

No Drawing. Application filed January 3, 1927. Serial No. 158,818.

This invention relates to the preparation of halogenated aromatic hydrocarbons; particularly of condensed nucleus type; and it is among the objects of the invention to provide improved procedure capable of excellent yields. Other objects and advantages will appear as the description proceeds.

To the accomplishment of the foregoing and related ends, the invention, then, consists of the features hereinafter fully disclosed, and particularly pointed out in the claims, the following description setting forth in detail a few of the various forms in which the principle of the invention may be applied.

In accordance with our invention, naphthalene is treated with a halogen while in a vehicle comprising a lower molecular weight compound containing a plurality of atoms of carbon and of hydrogen, that is, a hydrocarbon or halogenated hydrocarbon, as for instance benzene, toluene, xylenes, chlorobenzenes and the like, ordinary temperatures being suitable. Paraffin hydrocarbons may be used, but if contaminating olefins be present, there is a waste of the halogen.

We prefer to also include a catalyst, as iron, manganese, molybdenum, antimony, aluminum, FeCl_3 , etc.

As an illustrative example: Into 150 parts by weight of naphthalene and 300 parts of benzene, in the presence of iron as catalyst, chlorine is passed until about 0.8 mol. of chlorine is absorbed. Hydrochloric acid remaining in solution is removed by addition of soda ash and any excess of this together with resulting sodium chloride, is separated by filtration or decanting. On distillation of the filtrate about 95% of the benzene employed is removed, and about an 85% yield of alphachloronaphthalene on reacted naphthalene is obtained.

If the chlorination be continued until two mols. of chlorine are absorbed, a yield of dichloronaphthalenes is obtained. Instead of starting with the naphthalene as a batch charge, the naphthalene or the like may be supplied as the reaction proceeds.

In analogous manner, naphthalene may be

treated with bromine, to the formation of brom-derivatives.

Other modes of applying the principle of the invention may be employed, change being made as regards the details disclosed, provided the steps stated in any of the following claims, or the equivalent of such, be employed.

We, therefore, particularly point out and distinctly claim as our invention:—

1. A process of making mono and di halogen substituted naphthalene derivatives which comprises subjecting naphthalene to the action of not more than the theoretically required proportion of a halogen in a liquid vehicle included within the group consisting of benzene, toluene, the xylenes and chlorobenzenes.

2. A process of making mono and di halogen substituted naphthalene derivatives which comprises subjecting naphthalene in the presence of a catalyst to the action of not more than the theoretically required proportion of a halogen in a liquid vehicle included within the group consisting of benzene, toluene, the xylenes, and chlorobenzenes.

3. A process of making mono and di chloro-substituted naphthalene derivatives which comprises subjecting naphthalene to the action of not more than the theoretically required proportion of chlorine in a liquid vehicle included within the group consisting of benzene, toluene, the xylenes, and chlorobenzenes.

4. A process of making mono and di chloro-substituted naphthalene derivatives which comprises subjecting naphthalene to the action of not more than the theoretically required proportion of chlorine in a liquid vehicle included within the group consisting of benzene, toluene, the xylenes, and chlorobenzenes, and in the presence of a catalyst.

5. A process of making an α -halogen naphthalene which comprises reacting upon naphthalene with slightly less than one molecular equivalent of a halogen in a liquid vehicle included within the group consisting of benzene, toluene, the xylenes, and chlorobenzenes.

6. A process of making an α -halogen naph-

thalene which comprises reacting upon naphthalene in the presence of a catalyst with slightly less than one molecular equivalent of a halogen in a liquid vehicle included within the group consisting of benzene, toluene, the xylenes, and chlorobenzenes.

7. A process of making α -chloronaphthalene which comprises reacting upon naphthalene with slightly less than one molecular equivalent of chlorine in a liquid vehicle included within the group consisting of benzene, toluene, the xylenes, and chlorobenzenes.

8. A process of making α -chloronaphthalene which comprises reacting upon naphthalene in the presence of a catalyst with slightly less than one molecular equivalent of chlorine in a liquid vehicle included within the group consisting of benzene, toluene, the xylenes, and chlorobenzenes.

9. A process of making α -chloronaphthalene, which comprises reacting upon naphthalene with slightly less than one molecular equivalent of chlorine in a vehicle of benzene.

25 10. A process of making α -chloronaphthalene, which comprises reacting upon naphthalene in the presence of a catalyst with slightly less than one molecular equivalent of chlorine in a vehicle of benzene.

20 Signed by us this 23rd day of December, 1926.

EDGAR C. BRITTON.
WILLIAM ROBERT REED.
